CIRCUIT CLOSER

Frank M. Blum, Milwaukee, Wis., assignor to
Harnischfeger Corporation, Milwaukee, Wis., a
corporation of Wisconsin

Application March 29, 1937, Serial No. 133,522

1 Claim. (Cl. 200—16)

The invention relates to circuit closers.

The main object of the invention is to provide a circuit closure for controlling a plurality of electrical circuits which are successively made or broken by the reciprocatory movement of a single plunger member under the control of the operator. More particularly the invention includes an insulating casing having contact bars of different lengths mounted therein and a plunger carrying a series of ball contacts adapted to engage said bars, said balls also being in constant contact with a common conductor mounted on said plunger.

The invention further consists in the several features hereinafter set forth and more particularly defined by the claim at the conclusion hereof.

In the drawing:

Fig. 1 is an elevation view of a circuit closer embodying the invention, parts being broken away and shown in section along the line 1—1 of Fig. 2;

Fig. 2 is a detail horizontal sectional view taken on the line 2—2 of Fig. 1;

Fig. 3 is a detail horizontal sectional view taken on the line 3—3 of Fig. 1;

Fig. 4 is a view of a wiring diagram including the circuit closer;

Fig. 5 is a top plan view of one of the parts of the plunger;

Fig. 6 is an expanded view of parts of the plunger head, one of the parts being shown in section, the section being taken along the broken line 6—6 of Fig. 3, the other part being shown in dotted lines.

Referring to the drawing, the numeral 7 designates a base of suitable insulating material, 8 a housing of insulating material mounted on said base and secured thereto by clamping screw bolts 9, and 10 a plunger of suitable insulating material having a round shank 11 working in an opening 12 in the housing and a head 13 carrying a plurality of contacts hereinafter described.

45 The housing 8 has a hollow hexagonal interior 14 providing six side walls in each of which a contact plate 15 is inset and secured by a clamping screw 16 which passes through an opening 17 in each wall and cooperates with a screw 18 in threaded engagement with the threaded bore 19 in the screw 16 to form a binding post for one of the circuit wires. The plates 15 are shown in Fig. 4 and numbered 1 to 6, all of the plates except 1 and 2 being of different lengths.

The head 13 of the plunger has an internally threaded metal insert 20 about which it is cast providing an anchorage for a holding screw 21 which secures an auxiliary hexagonal head member 22 of insulating material to it, the head of the screw engaging a metal insert 23 in said member 22 to secure it for movement with the head part 13. The head part 13 has a hexagonal portion slidably fitting the walls of the housing 8 and provided with an annular surface 24 10 providing a seat for a contact plate 25 and provided with six hexagonally spaced depending nibs or tongues 26.

The head part 13 has a cylindrical bottom portion 27 provided with a conical end 28, and 15 these parts fit into a similar cavity 29 formed in the head part 22. The sides of the cavity 29 are not continuous but are intercepted by inclined grooves 30 whose axes are located in planes normal to the side walls of the head 20 member 22. The side walls of the member 22 are provided with centrally disposed longitudinally extending grooves 31 which merge with radially extending top grooves 32 whose inner ends 33 are of reduced width as shown in Fig. 3, 25 the grooves 32 and 33 cooperating to form pockets for the contact balls 34 and the inclined grooves 30 extending to the grooves 32 and 20 cooperating with the conical end 28 and insert 23 to form pockets for the coil springs 35, each 30 of which engages a ball 34 and forces it upwardly against the contact plate 25 and at the same time yieldingly presses the ball laterally so that it will engage the side wall of the housing and the contact plate 15 associated therewith. The balls in their outward position engage the tongues 26 which also assist in holding the balls in their pockets during the assembly of the device.

The grooves 31 are almost as wide as the 40 plates 15, and the sliding connection between the housing and the head part 22 is made at the parts of said head member facing the corners of said housing.

The plunger is normally held in an upper off 45 position by a spring 36 interposed between the head thereof and the base 7.

The balls 34 are always in contact with the plate 25 and hence always in circuit with each other, and as shown in Fig. 4 when the plunger 50 is moved downwardly, the balls for the plates 1 and 2 are first engaged which acts to establish a circuit from a current supply conductor 37 through conductor 38, plates 1, 25, and 2, conductor 39 through an electroresponsive de- 55

vice 40, conductor 41 to the other supply wire 42. Similarly as the plunger is pressed further inwardly, the supply circuit from the plate 1 is successively connected to the electroresponsive devices 43, 44, 45, and 46 connected in circuit with the plates 3, 4, 5, and 6 and the conductor 42. Thus the devices 40, 43, 44, 45, and 46 are successively energized to control circuits to other electrical apparatus. Conversely the gradual release of the spring pressure on the plunger causes it to move upwardly to successively cut out the control circuits. These electroresponsive devices may be of various kinds, such as electromagnetic contactors for establishing circuits of greater current carrying capacity than those controlled by the device described herein.

With this device as the balls 34 are always yieldingly engaged with the contact plate 25 and yieldingly engage the plates 15 as they move over them, good circuit connections are assured and the springs do not take the current.

I desire it to be understood that this invention is not to be limited to any particular or specific arrangement of parts except in so far as such limitations are included in the claim.

What I claim as my invention is:

In a circuit closer, the combination of a hollow housing of insulating material having a polygonal interior, a plunger reciprocating in said housing and having a two-part head of insulating material provided with pockets for contact balls and inclined spring pockets, means securing the parts of said head together, contact plates of varying length mounted in the walls of said housing, contact balls mounted in said first named pockets, a contact plate on said plunger with which all of said balls engage, springs mounted in said spring pockets and urging said balls against said last named contact plate and laterally into engagement with the walls of said housing.

FRANK M. BLUM.
